Atty.

UNITED STATES PATENT OFFICE.

WALTER C. BECKWITH, OF FOSTORIA, OHIO.

DEVICE FOR RAISING SUNKEN VESSELS.

1,353,623.

Specification of Letters Patent. Patented Sept. 21, 1920.

Application filed January 24, 1920. Serial No. 353,647.

To all whom it may concern:

Be it known that I, WALTER C. BECKWITH, citizen of the United States of America, residing at Fostoria, in the county of Seneca 5 and State of Ohio, have invented certain new and useful Improvements in Devices for Raising Sunken Vessels, of which the following is a specification.

The object of the invention is to provide 10 an improved apparatus for elevating submerged vessels.

Other and more specific objects will be in part obvious and in part described as the specification is proceeded with.

15 In the accompanying drawings forming part of this specification:

Figure 1 is a perspective view showing my invention in operation;

Fig. 2 is a plan view of the elevating 20 mechanism; and

Fig. 3 is a side view of one of the collapsible pontoons.

Referring more specifically to the drawings wherein like reference numerals refer 25 to corresponding parts throughout the several views, 1 denotes the sunken vessel and 2 a floating body anchored there above by suitable moorings (not shown). The floating body 2 may consist of a barge, pontoon, 30 raft or the like. While only one floating body 2 is shown any number could be employed, placed end to end or in rows.

The numeral 3 denotes a plurality of lifting cables preferably arranged in pairs, the 35 cables of each pair being connected at their lower ends to opposite sides of the sunken vessel, by any improved fastening means indicated at 4. These cables pass over idler rollers 5 and sheaves 6 attached to opposite 40 sides of the floating body 2, it being understood that there will be an idler and a sheave for each cable and that an idler and a sheave on one side of the floating body, will preferably be identical with and located diametrically opposite to the idler and sheave on the other side. After passing over the idlers 45 and sheaves the cables are connected at their upper ends to rocking frames 7 any suitable number of which may be employed. These frames comprise spaced uprights 8 50 pivoted to the side of the floating body as at 9 and pivotally connected together at their upper ends as at 10 by means of a horizontally disposed connecting rod 11. It 55 is to be understood that the number of rocking frames on each side of the floating body

will vary according to the number of pairs of lifting cables employed.

The purpose of the rocking frames is to provide leverage for lifting the sunken vessel through the medium of the lifting cables. These frames are rocked upon their pivots 9 by means of cables 20 extending from the top of uprights 8 to power or hand operated winches 21. Any desired leverage 60 or length of pull can be obtained by elevating or lowering the point of connection between the cables 3 and the uprights 8 as preference or necessity may dictate.

In order to increase the buoyancy of the 70 sunken vessel and thereby aid in the raising operation I attach a plurality of collapsible air bags or containers 12 to the lifting cables 3, preferably one container for each pair of cables. Attachment may be 75 made in any suitable manner, as by means of short ropes or wires 13 leading from the cables to a reinforcing tape or the like 14 with which the containers are provided. The containers are made of any approved 80 collapsible material capable of withstanding great strain.

Considerable difficulty has been encountered in overcoming the great strain to which these air containers are subjected to 85 when attached to vessels submerged in very deep water. This difficulty is overcome in the present invention in two ways. First by attaching the bags to the lifting cables some distance above the sunken vessel instead of 90 placing them within or attaching them directly to the sunken vessel and thereby avoiding the greater pressure encountered at the lower depths, and second by providing the bags with an equalizing valve 15, 95 the operation of which will presently be explained.

In practice the cables 3 are attached to the sunken vessel by a diver. The bags 12 are then lowered in deflated or partially deflated condition and after attachment to the lifting cables are inflated by any means (not shown) or the bags may be lowered after inflation. The valve 15 is so constructed that when the pressure within the bag becomes 100 sufficiently greater than the pressure without the bag to damage the same, as during inflation operation, the valve will open and permit the air to escape until the internal pressure has been relieved. Likewise, this 105 action occurs when the inflated bag is being brought to the surface. Conversely the valve

15 is designed to remain closed during the inflation operation under the water only until the pressures are equalized when it will automatically open. Any well known and 5 approved form of valve may be employed for this purpose.

When the rocking frame has been moved to the dotted line position shown in Fig. 1, and the submerged vessel raised with respect to the floating body 2, the cables 3 are 10 made fast in any desired manner as to idler pulleys 5 and the slack taken up by returning the frame to full line position and adjusting the connection between the rocking 15 frame and the cables. Movement of the rocking frame in the direction of the arrow, Fig. 1 is repeated and the slack of cables 3 taken up until the submerged vessel has either been raised to the surface or raised 20 sufficiently to permit of its being towed to shallow water.

Having thus described my invention what I claim is:

1. An apparatus for raising sunken vessels, comprising a buoyant body, a frame 25 pivotally secured to said buoyant body, lifting cables secured at opposite ends to said

frame and to said sunken vessel and passing over sheaves carried by said floating body and means for rocking said frame. 30

2. An apparatus for raising sunken vessels, comprising a buoyant body, a frame pivotally secured to said buoyant body, lifting cables secured at their upper and lower ends respectively to said frame and to the 35 sunken vessel, and means for rocking said frame on its pivot, comprising a cable and winch.

3. An apparatus for raising sunken vessels, comprising a buoyant body, a frame, said 40 frame having upright members pivotally secured to said buoyant body at their lower ends and connected together at their upper ends by a horizontally disposed member, lifting cables connected to said upright members and to said sunken vessel, and means for rocking said frame to place said lifting cables under tension. 45

In testimony whereof I affix my signature in presence of two witnesses.

WALTER C. BECKWITH.
